CLAIM

The ornamental design for a pet trainer transmitter and receiver set as shown and described.

DESCRIPTION

FIG. 1 is a front perspective view of the transmitter component of the pet trainer transmitter and receiver set according to the present design, shown separately for clarity; FIG. 2 is a rear perspective view thereof; FIG. 3 is a front elevation view thereof; FIG. 4 is a rear elevation view thereof; FIG. 5 is a left side view thereof; FIG. 6 is a right side view thereof; FIG. 7 is a top view thereof; FIG. 8 is a bottom view thereof; FIG. 9 is an exploded rear perspective view thereof; FIG. 10 is a front perspective view of the receiver component of the pet trainer transmitter and receiver set, shown separately for clarity; FIG. 11 is a rear perspective view thereof; FIG. 12 is a front elevation view thereof; FIG. 13 is a rear elevation view thereof; FIG. 14 is a left side view thereof; FIG. 15 is a right side view thereof; FIG. 16 is a top view thereof; FIG. 17 is a bottom view thereof; and, FIG. 18 is a perspective view of the pet trainer transmitter and receiver set. The dash-dash broken lines in the drawings depict portions of the pet trainer transmitter and receiver set that form no part of the claimed design.

1 Claim, 18 Drawing Sheets
